UNITED STATES PATENT OFFICE.

ORA H. JEWETT, OF ST. PAUL, INDIANA.

BOTTLE.

1,055,400.

Specification of Letters Patent. Patented Mar. 11, 1913.

Application filed June 25, 1912. Serial No. 705,750.

To all whom it may concern:

Be it known that I, ORA H. JEWETT, a citizen of the United States, residing at St. Paul, in the county of Decatur and State of Indiana, have invented certain new and useful Improvements in Bottles, of which the following is a specification.

The object of this invention is to provide a glass bottle of such construction that the removal of its original contents will compel the mutilation of the bottle to such an extent that it cannot be again used without the mutilated portion acting as a tell-tale of such second use, and the object, also, is to provide a device of the above character which will not interfere with the full and free use of the original contents of the bottle.

I accomplish the objects of the invention by the mechanism illustrated in the accompanying drawing, in which—

Figure 1, is side elevation and partial vertical section of a bottle embodying my improvements, the view showing the cap surrounding the neck but raised above the shoulder of the bottle. Fig. 2 shows the bottle in vertical section with the cap seated in the neck, the cap being in part side elevation and part vertical section, and Fig. 3 is a detail in vertical section on a larger scale of a modified form of my device.

Like characters of reference indicate like parts throughout the several views of the drawing.

1 is the body of the bottle, 2 the neck, both of any suitable and usual construction, and 3 is the shoulder of the bottle which differs from the usual construction in that it is provided with an annular channel 4 surrounding the neck. This channel will preferably be formed with screw-threads 5 in its outer walls.

6 is a cap, preferably made out of glass in the form of an inverted cup which has an opening to its interior only at its lower end. This lower end of the cup 6 is provided with screw-threads 7 on its outer periphery, and this threaded end of the cap is adapted to be screwed loosely into the channel 4 in the neck of the bottle. Before the threaded end of the cap 6 is introduced into the channel 4 the latter is partially filled with a suitable cement, plaster or other sealing material which will be in a plastic condition when introduced into the channel and also while the cap is being

screwed into place in said channel, but which will afterward become hard and set so as to prevent the removal of the cap. The threaded end of the cap will make a 60 sufficiently loose fit in the channel 4 to permit the cement 8 to be forced up around the end of the cap between it and the wall of the channel 4, as shown in Fig. 2. The cap 6 will preferably be provided with an 65 annular outer shoulder 9 at the limit of its threaded portion, to make a neat finish above and to protect the cement material 8. The inner wall of the cap will also be provided with a flange or bead 10 to stop 70 the insertion of the end of the cap into channel 4. In order to more effectually prevent the turning and unscrewing of the cap in channel 4 after it has been cemented in said channel, I prefer to provide the 75 lower end of the cap with indentations or notches 12, into which the cement will enter and harden and serve as a lock against any possible rotary and unscrewing movement 80 of the cap.

The manner of using my invention is as follows: The bottle 1 is first filled with the material which it is intended to contain, and the neck 2 is then closed by means of a cork 13 in the usual manner. Then the desired 85 quantity of cement is introduced into the channel 4, and thereupon the inverted glass cap 6 is introduced and screwed into the channel 4 as far as it will go, that is, until arrested by the bead 10. After the cement 90 has hardened the removal of the cap 6 is impossible without breaking the cap. This will be accomplished by any of the well known and usual methods thereby exposing the neck 2 and its stopper or cork 13 and 95 by the withdrawal of the cork 13 the contents of the bottle is available. When a desired quantity, less than the contents of the bottle, has been used the remainder may be preserved by replacing the cork 13 in the 100 usual manner. On account of the portion of the cap 6 which must always remain in the bottle this remaining portion will act as a tell-tale to indicate that the bottle has been opened and its original contents removed or tampered with, and the public will thus be warned against any attempt 105 to place spurious merchandise in the original package.

In the modification, shown in Fig. 3, the 110 outer wall of the channel is beveled inwardly to retain the cement and the

threaded construction is omitted. The end of the cap 6 is made wedge-shape, as shown, so that when introduced into the channel in the neck of the bottle and the cement applied the space between the oblique walls of the cap and of the channel will be filled with a key of cement that will effectually prevent the removal of the cap. The lower edge of the cap may be notched or corrugated, as shown in Fig. 1 or as indicated by dotted lines in Fig. 3, to receive the cement and prevent any rotary movement of the cap in the channel of the shoulder.

While I have described my invention with more or less minuteness as regards details of construction and arrangement and as being embodied in certain precise forms, I do not desire to be limited thereto unduly or any more than is pointed out in the claims. On the contrary, I contemplate all proper changes in form, construction, and arrangement, the omission of immaterial elements

and the substitution of equivalents, as circumstances may suggest or necessity render expedient.

25

I claim—

The combination of a bottle having a hollow neck and an annular channel around the neck, said channel having screw-threads in its wall, an inverted cup-shaped cap surrounding said neck having screw-threads in its wall adjacent its open end and having indentations in its end, said threaded-end being screwed into the threaded channel in the neck of the bottle and cement in the channel to seal the joint.

In witness whereof, I, have hereunto set my hand and seal at Indianapolis, Indiana, this 10th day of June, A. D. one thousand nine hundred and twelve.

ORA H. JEWETT. [L. S.]
